HOSE REELING MECHANISM

Ralph B. Ziegler, Philadelphia, Pa., assignor to
 Philadelphia Valve Company, Philadelphia, Pa.,
 a corporation of Pennsylvania

Application June 2, 1950, Serial No. 165,713.

5 Claims. (Cl. 242—86)

1

This invention relates to hose reeling mechanism. More specifically, it is concerned with hose reeling mechanism intended to be used in dispensing petroleum products like gasoline or oil at airports in servicing planes and other flying craft.

In hose reeling mechanism, as ordinarily constructed, the reel on which the hose is wound is horizontally arranged; and in instances where the liquids are metered, the sealers require the hose to be drained after each delivery to prevent cheating of the purchaser. With a horizontal reel however, some of the liquid will always remain in the bottom of the convolutions or turns of the hose. Since trapped liquid cannot be completely removed by pump action, it is impossible to determine, with any degree of accuracy, any fixed amount that should be allowed the purchaser as a deduction from the reading of the meter at the time a sale is made.

The chief aim of my invention is to overcome the drawbacks to which reference is made above. This objective is attained in practice as herein-after more fully disclosed, through provision of an improved hose reeling mechanism adapted for installation in a pit below the ground level, in which the reel is vertically arranged and rotatively supported, in which the hose extends up through an aperture in a cover over the pit, and in which the reel has a spiral ledge at the bottom whereon the lowermost convolution of the hose is supported with the succeeding convolutions piled up upon it to insure complete drainage.

In connection with a hose reeling mechanism having the foregoing attributes, it is a further aim of my invention to provide automatically-operative means for guiding and controlling the hose to predetermine uniform distribution of its turns on the reel during winding, as well as to prevent snarling thereof incident to withdrawal from the pit.

Still another object of my invention is to provide a simple and reliable power drive means for driving the reel in winding, with means which will allow reverse rotation of the reel by manual pull upon the hose in unwinding.

Other objects and attendant advantages will appear from the following detailed description of the attached drawings, wherein: Fig. 1 is a fragmentary view in vertical section of a pit containing my improved hose reeling mechanism.

Fig. 2 is an elevation of the mechanism looking as indicated by the angled arrows II—II in Fig. 1.

Fig. 3 shows the apparatus in top plan;

Fig. 4 is a diagrammatic view showing the wir-

2

ing connections and controls for an electric motor which I employ as the power source to operate the mechanism.

Fig. 5 is a fragmentary view, partly in elevation and partly in vertical section, of an electrically actuated clutch device embodied in the reel driving mechanism.

As herein exemplified, my improved hose reeling mechanism comprises a vertically-arranged reel 5 with a cylindric drum which may be conveniently fashioned from sheet metal, and with spoked wheel-like ends 6 and 7 respectively at the top and bottom. Extending axially down into the drum through a central hub element 8 of the top wheel end 6 is a shaft 9 whereof the upper end is journaled in a bearing 10. From Figs. 2 and 3 it will be noted that the bearing 10 is fixedly supported by a channel beam 11 forming part of a structural iron skeleton framework 12 set into a pit 13 below the ground level. At its lower end, the shaft 9 is secured in the upstanding boss 15a on one elbow 15 bolted to the bottom head 7 of the drum 5. The downward portion of the elbow 15 extends axially through the lower drum head 7 and mates with a fixed elbow 16, the two elbows together constituting what is ordinarily known as a swivel fitting which, in this instance, serves to rotatively support the reel 5 at the bottom. The fixed elbow 16 of the swivel fitting is welded or otherwise rigidly secured to a cross member 17 of the framework 12, and is in communication by way of a pipe 18 with a source of supply (not shown) of the liquid commodity to be vended. The delivery hose, designated 20, is connected to the horizontal outlet branch of the elbow 15 and coiled about the drum with its free end portion passing tangentially from the drum as in Fig. 2 and then upward and outward through an aperture 21 in a cover plate 22 that closes the pit 13 at the top as in Fig. 1. A spiral ledge 23 having a circumferential extent of about 270° peripherally of the bottom head 7 of drum 5 serves as a support for the lowermost convolution of the hose 20 and determines the winding pitch angle for the latter.

For the purpose of power actuating the drum 5 to take up the hose, I have shown means including an electric motor 25 which is suitably supported near the top of the pit 13 from another horizontal member of the skeleton framework 12, and with which is incorporated a housing 26 for speed reduction gearing (not shown) with an upwardly extending out-put shaft 27. Mounted on shaft 27 is a sprocket pinion 28 which, through a chain 29, imparts rotary motion to a sprocket

wheel 30 affixed to the drum shaft 9 immediately below the upper bearing 10 for the latter. The sprocket pinion 28 is connected to the shaft 27 by a clutch device 31 of a well known commercial type having a release plunger 32.

The means which I have devised for controlling the hose 20 to insure even winding thereof on the drum 5 comprises a flanged wheel 35 which is circumferentially configured to conform to the cross section of the hose, and which is adapted to roll on top of the convolutions or turns of the latter as best shown in Fig. 1 during winding and unwinding. The wheel 35 revolves freely about a horizontal axis stud 36 projecting laterally from a slide carriage 37 which is constrained to movement on guide rods 38, 39 extending vertically between the horizontal member 11 at the top of the framework 12 and a corresponding member 40 at the bottom. As shown in Fig. 2, the carriage 37 is attached to an endless chain 41 which is trained about sprocket pinions 42 and 43 whereof the latter rotates freely about a lateral stud 44 on a bracket 45 mounted on the frame member 40. The sprocket wheel 42 is affixed to a horizontal axis shaft 47 rotatively supported by another bracket 48 on the framework, together with a miter gear pinion 49 which is in mesh with a companion miter pinion 50 free to rotate about a stud 51 upstanding from said bracket. Secured to the pinion 50 is a sprocket wheel 52 which, through a chain 53, is adapted to be driven from a sprocket pinion 54 from the output shaft 27 of motor 25.

As shown diagrammatically in Fig. 4, the motor 25 is connected to a three wire electric power line 55 with interposition of relays (not illustrated) in a box 56, and can be started by a manual push button switch indicated at 57, when the reel 5 is to be actuated to take up the hose 20. Also embodied in this electric system is a limit switch 58 which, see Fig. 1, is secured to the guide rod 39 near the top for actuation of its plunger 59 by the carriage 37 when the latter is fully elevated and the hose 20 is completely wound up on the reel. Also embodied in the wiring system is a solenoid 60 which, see Fig. 2, is supported by a standard 61 from the frame of motor 25 with its armature 62 in axial alignment with the actuating plunger 32 of the clutch 31, and subject to a spring 63 to normally hold the clutch released.

In order to prevent kinking of the hose 20 as it is passed downward into or upward from the pit, and tangentially to or from the drum 5, I have provided a group of guide rollers 65, 66 and 67 which are supported for free rotation by a laterally extending bracket 68 welded to the frame 12 at the top of the latter.

Although, as already stated, the clutch 31 is of a well known type, its construction will be briefly described in connection with Fig. 5 in order that its use in connection with my invention may be properly understood. As shown, it includes a drum element 70 which is secured to the shaft 27 by a set screw 71. Rotatable about the lower portion of the drum element 70, with interposition of a pin bearing 72, is a collar 73 where-to are bolted the sprocket pinions 28 and 54. Anchored in an annular groove in the top of collar 73 and extending upward about the top portion of element 70 is a coiled spring 75 whereof the free end is coned. The plunger 32 is slideable endwise in the axial bore of the drum 70 and urged outwardly by a biasing spring 76. Extending crosswise through the plunger 32 is a pin 77 which

is constrained in a diametral slot in the top of the drum element 70, with its ends engaging through aligned apertures in a ring 78 which is flared to correspond with the cone taper of clutch spring 75. Normally, the collar 73 is free to rotate about the drum 70. However upon depression of the plunger 32 and the ring 78 being brought into engagement with the top of spring 75, the latter is caused to bind upon the drum 70 with the result that the collar 73 and the sprocket pinions 28 and 54 will be clutched to and driven by shaft 27.

Operation

With the clutch 31 normally released, the hose 15 20 can be manually withdrawn from the pit incident to which the reel 5 will freely revolve on its axis. Through the gearing 30, 29, 28, 54, 53, 20 52, 50, 49 and chain 41, the carriage 37 will be concurrently moved downward on the guide rods 38 and 39 for control of the hose by the flanged wheel 35. Upon delivery of the desired amount of the liquid commodity, the button of manual switch 57 is pressed to start the motor 25, with incidental energization of the solenoid 60 and setting of the clutch 31 for drive of the various gear connections by power from said motor. Through the gearing, the reel 5 is rotated to draw in the hose 20, while the carriage 37 is compensatively elevated to control, through its flanged wheel 35, uniform winding of the hose about the reel. Eventually, current flow to the motor 25 will be interrupted through opening of the limit switch 58 by the carriage 37 when the desired amount of the hose has been wound upon the reel. As the winding takes place, the successive convolutions of the hose will be piled one upon another, all at the inclination determined by the spiral ledge 23 at the bottom of the reel so that complete draining may take place. It is to be understood that the push button switch 57 is suitably located for convenience of ready access above ground.

Having thus described by invention I claim:

1. In hose reeling mechanism, a vertically-arranged winding drum having an axial shaft extension at the top thereof; a vertically-arranged drive shaft adjacent the drum; sprocket wheels respectively on the drum shaft and on the drive shaft and a chain connecting them; control means guided for up and down travel adjacent the drum for controlling the hose as it is wound or unwound; a pair of vertically-spaced horizontal axis sprocket wheels and a connecting chain whereto the hose control means is attached; a bevel gear affixed to the upper of the two horizontal axis sprockets; an intermeshing bevel gear rotative about a vertical axis; a sprocket wheel affixed to the last mentioned bevel gear; another sprocket wheel on the drive shaft; and a chain connecting the two last mentioned sprocket wheels.

2. Hose reeling mechanism according to claim

1 adapted for accommodation in a pit below ground, wherein the hose is passed through an aperture in a cover over the pit, and further including a group of guide rolls arranged above the drum to direct the hose at a tangent to the drum enroute to and from the aperture in the pit cover.

3. Hose reeling mechanism according to claim

1, wherein the hose control means is in the form of a freely revolving roller engaging the hose from beneath and having a flange urging the hose toward the reel drum surface.

4. Hose reeling mechanism according to claim

1, further including an electric motor with an

associated speed reducer coupled to the drive shaft for use in winding the hose by power; and a normally-released clutch means between the drive shaft and the two sprocket wheels associated therewith, permitting free rotation of the drum by draw upon the hose in unreeling.

5. Hose reeling mechanism according to claim 1, further including a normally-released magnetically-actuated clutch means between the drive shaft and the two sprocket wheels associated therewith; an electric motor coupled to the drive shaft; and circuit in which the motor and the magnetic-actuating element of the clutch means are interposed with a control switch for simultaneous operation and excitation.
